UNITED STATES PATENT OFFICE.

NELS NELSON, OF KINGCOME RIVER, BRITISH COLUMBIA, CANADA.

AUTOMATIC VALVE-CONTROLLING DEVICE.

1,262,689.

Specification of Letters Patent. Patented Apr. 16, 1918.

Application filed June 7, 1917. Serial No. 173,357.

To all whom it may concern:

Be it known that I, NELS NELSON, a subject of the King of Great Britain, residing at Kingcome River, in the Province of British Columbia, Canada, have invented certain new and useful Improvements in Automatic Valve-Controlling Devices, of which the following is a specification.

My invention relates to improvements in automatic cut-off devices, and the object of my invention is to provide a device for use with air pumps and the like for the automatic regulation of the air pressure created by the pump and which device is simple, practical and of a highly efficient character.

I attain this object by the construction illustrated in accompanying drawings in which—

Figure 1 is a view illustrating the practical application of my device to an air pump cylinder head.

Fig. 2 is a plan view of Fig. 1.

Fig. 3 is an end view of Fig. 1.

Similar figures of reference indicate similar parts throughout the several views.

1 indicates a typical air pump cylinder head in which are mounted the suction valve 2 and the discharge valve 3, the valve 3 opening to the discharge pipe 4, on which 30 pipe are arranged T-connections 5 and 6 and in which connections are mounted respectively the air pressure gage 7 and safety valve 8, the pipe or nipple 9 which carries the gage 7 being provided with a T-connection 10.

Secured into the head 1 on each side of the stem 11 of the valve 2 are studs 12 and 13, on the upper ends of which are rigidly supported two plates 14 and 15, these plates 40 being spaced apart by distance pieces 16, as shown more particularly in Fig. 3, and through the lower plate 14 the upper end of the stem 11 slidably extends. Movable mounted on the hood 17 which incloses the 45 stem of the discharge valve 3 is a bell crank lever 18, the long arm of which extends between the plates 14 and 15 and normally to one side of the stem 11, while to the short arm of the lever 18 is connected a lever 19, the free end of which is connected to the 50 end of an elliptical spring tube 20, similar to those found in pressure gages, the other end of which tube is provided with a threaded tubular connection 21 by means of which 55 it, the spring tube, is connected to the T-

connection 10, hereinbefore mentioned. The lever 19 is slotted toward its free end to permit of the adjustment of the spring tube, as it will be seen that, by slackening the bolt 22, which extends through the slot 23 and the short bar 24 which connects the lever 19 and tube 20 together, it, the bar, may be moved along the lever 19 in either direction to regulate the tension of the tube.

The manner in which the device operates 65 may be briefly described as follows:—The pump being in operation and the pressure rising in the pipe 4 and acting on the elliptical tube 20 through pipe 9 and connection 21, the tube will tend to straighten out, thus 70 drawing over the lever 19 to move the bell crank 18 until when the maximum pressure is reached its long arm is horizontal and positioned directly over and bearing on the end of stem 11 of the suction valve, holding it down so that it cannot completely 75 close, thereby allowing the air in the cylinder to escape back through the suction valve seat and thus prevent the air pressure from rising above the required amount. On the 80 pressure falling, the spring tube 20 and the lever 19 return to their normal positions, the long arm of the bell crank 18 being thereby swung clear of the stem 11, allowing the valve 2 to resume its normal opera- 85 tion.

What I claim as my invention is:—

1. The combination with the suction valve of an air pump, of a laterally movable lever disposed to one side and normally clear of the stem of said valve, and means for moving said lever laterally to a position above the end of said stem when a maximum air pressure is reached so as to prevent seating of the said valve. 95

2. The combination with the suction valve of an air pump, of a laterally movable lever disposed normally clear of the stem of said valve, and pressure operated means for moving said lever laterally to a position above the end of said stem when a maximum pressure is reached so as to prevent seating of the said valve. 100

3. The combination with the suction valve of an air pump, of a suitably fulcrumed lever having its long arm arranged adjacent and normally clear of the stem of said valve, a lever connected at one end to the short arm of the fulcrumed lever, and a curved tubular connection between the free 110

end of the second mentioned lever and the air discharge pipe.

4. The combination with the suction valve of an air pump, of a suitably fulcrumed lever having its long arm arranged adjacent and normally clear of the stem of said valve, a lever connected at one end to the short arm of the fulcrumed lever, and a curved tubular connection between the free 10 end of the second mentioned lever and the air discharge pipe, said tubular connection being adjustably secured to the said lever.

5. The combination with the suction valve of an air pump, of a suitably fulcrumed 15 lever having its long arm arranged adjacent and normally clear of the stem of said valve, a lever connected at one end to the short arm of the fulcrumed lever, and an elliptical tube connected at one end to the 20 air discharge pipe bent round and connected

at its other end to the free end of the second mentioned lever.

6. The combination with the suction valve of an air pump, of a pair of suitably supported superposed plates through the lower 25 of which the end of the suction valve stem normally extends, a suitably fulcrumed lever having its long arm extending between said plates and normally to one side of the said stem, a second lever connected at one end 30 to the short arm of the fulcrumed lever and extending across the upper plate, and an elliptical tube connected at one end to the air discharge pipe bent round and adjustably connected at its other end to the said 35 second lever.

Dated at Kingcome Inlet, B. C., this 21st day of May, 1917.

NELS NELSON.
